SURVEYOR'S TAPE CLAMPING TOOL

Ray J. Peters, 744 Duke Circle, Pleasant Hill, Calif.

Filed Mar. 12, 1962, Ser. No. 69,214

Term of patent 14 years

(Cl. D54—13)

FIGURE 1 is a perspective view of a surveyor's tape clamping tool showing my new design.

FIGURE 2 is a view similar to FIGURE 1, but viewed from another angle.

FIGURE 3 is a side elevational view of the clamping tool as viewed from the side opposite that shown in FIGURES 1 and 2.

I claim:

The ornamental design for a surveyor's tape clamping tool, substantially as shown.
